UNITED STATES PATENT OFFICE.

CLIFFORD B. HIGGINS, OF DETROIT, MICHIGAN, ASSIGNOR OF ONE-HALF TO HARRY A. HIGGINS, OF DETROIT, MICHIGAN.

ART AND MECHANISM FOR DRAWING HOLLOW CYLINDRICAL METAL BODIES.

1,422,974.

Specification of Letters Patent. Patented July 18, 1922.

Application filed December 27, 1920. Serial No. 433,319.

To all whom it may concern:

Be it known that I, CLIFFORD B. HIGGINS, citizen of the United States, residing at Detroit, county of Wayne, State of Michigan, have invented a certain new and useful Improvement in the Art and Mechanism for Drawing Hollow Cylindrical Metal Bodies, and declare the following to be a full, clear, and exact description of the same, such as will enable others skilled in the art to which it pertains to make and use the same, reference being had to the accompanying drawings, which form a part of this specification.

My invention relates to the art of drawing hollow cylindrical metal bodies, commonly referred to as tubes or shells, for the sake of convenience hereinafter referred to as tubes, over a triblet or mandrel and particularly to the removal of the drawn cylinder from the mandrel. It is desired, however, not to limit this process to what are commonly known in the trade as tubes.

My invention consists in the process of hammering or swaging the tube on the mandrel as on an anvil thereby expanding the tube so that the mandrel may be easily withdrawn therefrom and in the means provided for accomplishing such object.

Figure 1 is an elevation of a drawing bench.

Fig. 2 is an enlarged plan view partly broken away.

Fig. 3 is a section taken on line 3—3, Fig. 2.

Fig. 4 is a section taken on line 4—4, Fig. 2.

Fig. 5 is an elevation showing a triblet carrying a tube.

Fig. 6 is an elevation of a triblet showing the tube partly in section.

In the drawing of metal tubes over a mandrel the mandrel carrying the tube is drawn through a draw-plate of lesser diameter than the tube, the tube being thereby reduced in gauge and diameter and increased in length. There is nothing new in this method of drawing metal tubes. The disadvantage, however, lies in the difficulty of removing the mandrel from the drawn tube. My invention relates to an improved process for removing the mandrel from the tube. I expand the tube on the mandrel by hammering the tube throughout its length and

circumference thereby facilitating its removal.

In accomplishing the above object I find the within described means particularly adapted for the purpose. I provide a draw-bench *a* which is equipped with an endless chain *b* mounted on sprockets *c* and *c*² as shown in Fig. 1 which chain may be driven by gearing as shown in Fig. 1. Separate links of this chain are adapted to be engaged by the hook of a reach-bar *d*. This reach-bar is secured to a carriage consisting of forward and rearward sections *e* and *e*² respectively which carriage is adapted to run back and forth in a provided runway *e*³. This carriage is provided with gripping jaws adapted to grip the end of a mandrel to draw the same along with the movement of the carriage as shown in Fig. 2.

These jaws are indicated as *f* and *f*² and are pivoted to each other and to section *e* of the carriage at *h*. The forward end of each of these jaws is serrated providing a good gripping surface. The end of each jaw opposite its gripping end is pivoted to section *e*² of the carriage by means of a link *i*, such links being pivoted to each other and to such carriage section at *g*. A tongue *k* is secured to the section *e*² of the carriage and pivotally connected with the reach-bar *d*.

At the head of the draw-bench is a draw plate *m* through which the tube is drawn to reduce its diameter and gauge.

When it is desired to draw a tube such as *o* a mandrel *p* is passed therethrough. This mandrel is of less diameter at one end for a portion of its length than at the other and the sections of varying diameters are separated by a shoulder *p*² as shown in Fig. 6. The portion of the mandrel of larger diameter is of course of less diameter than the interior diameter of the tube to be drawn. The end of the tube has been previously pointed as at *o*² to engage the shoulder *p*² of the mandrel. The smaller end of the mandrel which mandrel carries the tube as shown in Fig. 6 is now passed through an opening in the draw-plate and through the central opening in the swaging device which device is hereinafter more particularly described. The end of the mandrel is now gripped by the jaws *f* and *f*² as shown in Fig. 2. If the hook of the reach-bar *d* is now engaged over a link of the chain

b the movement of the chain will draw the mandrel and tube through the draw-plate *m* and through the swaging machine.

- The swaging or hammering device might 5 be of any conventional form. As shown in the drawings, it comprises a housing *n* within which a rotating spindle *r* is adapted to revolve. A flywheel *s* is mounted on the spindle so as to drive the same. *r*² is a bearing for the spindle within the housing. 10 Supporting standards for the device are indicated as *s*². The face of the spindle is slotted to receive a pair of dies *t* rounded on their inner ends after the manner of peening hammers which dies are held between a 15 pair of backers *t*². Outside of and around the spindle is an annular rack *q*² containing loosely a number of hardened steel rolls *q* which are separated from each other in individual pockets as indicated. The revolution 20 of this spindle causes the dies and backers to pass between successive pairs of opposing rolls which force the dies together. The spindle is hollow to permit the tube to 25 be fed through it. The dies revolve rapidly around the tube *o* carried by the mandrel *p* while the rack containing the rolls revolves more slowly being moved only by the slight motion of the rolls during the time 30 of contact with the backers. The dies are of hardened steel and they are adjustable as to projection by means of steel shims *u* which separate the die from its backers. *n*² is a gateway plate carried by the housing. 35 No claim is made to this swaging device as a tool, for with the exception of possibly the dies constructed in the manner of peening hammers, it is a well known form of swaging machine.
- 40 During the drawing process the mandrel and tube are drawn through the swaging device just after they leave the draw-plate. The swaging device would necessarily be adapted for the particular diameter of tube 45 drawn. As the mandrel and tube are drawn through the swaging device a multiplicity of hammer like blows or compression impulses are administered the exterior of the tube

throughout its circumference and length. With ten pairs of rolls as shown in Fig. 4, 50 were the spindle rotated at 400 revolutions per minute, not allowing for the slight movement of the ball rack, the blows upon or the closures of the dies would approximate 8000 per minute. These hammer blows expand 55 the tube so that after the tube is removed from the machine the mandrel can be easily withdrawn therefrom.

What I claim is:

1. In the art of drawing metal tubes over a mandrel, the method of removing the mandrel therefrom, which consists in hammering the tube on the mandrel so as to expand the tube in order that the mandrel may be withdrawn. 60
2. In the art of drawing metal tubes over a mandrel, the process of removing the mandrel from the tube which consists in hammering the tube throughout its length and circumference a sufficient number of 70 times to cause expansion of the tube permitting the withdrawal of the mandrel. 65
3. In the art of drawing metal tubes over a mandrel, drawing a mandrel carrying a metal tube through a draw-plate so as to reduce the gauge and diameter of the tube and increase its length, and striking the outer surface of the tube a multiplicity of blows throughout its length and circumference so as to cause expansion of the tube permitting 75 the withdrawal of the mandrel therefrom. 80
4. In a metal tube drawing machine, a draw-plate, means for drawing a mandrel and tube therethrough, means for hammering the tube on the mandrel as on an anvil as it moves along and after it leaves the draw-plate. 85
5. In a metal tube drawing machine a draw-plate through which a mandrel carrying a tube may be drawn, a hammering device aligned with said draw-plate adapted to hammer the tube throughout its length and circumference as it is drawn along after it 90 leaves the draw-plate.

CLIFFORD B. HIGGINS.
